EYE CONSTRUCTION FOR DOUBLE
BAR BUMPERS

Herbert S. Jandus and Norman Y. Kristensen,
Detroit, Mich., assignors to General Spring
Bumper Corporation, Detroit, Mich., a corpo-
ration of Michigan

Application April 25, 1931, Serial No. 532,850

14 Claims. (Cl. 293—55)

This invention has to do with bumpers, particularly of the character embodying a pair of impact bars, and has for its principal object to provide a connection between the pair of impact bars and a single back bar.

A further object of the invention resides in the provision of a special bolt construction for centering the end bolts for holding the eyes of the respective bars in proper relationship.

Another important object of the invention is to provide a double bar bumper, the impact bars of which are spaced very closely together.

In carrying out the invention, the impact bars have eyes whose adjacent portions are formed to provide an opening through which the eye of the rear bar may be inserted into the impact bar eyes. A bolt passes through the back bar eye, with its head resting on the top of the upper impact bar, a shouldered element being applied to the opposite end of the bolt to engage the bottom of the lower impact bar and tightly hold the respective eyes in interlocked relationship. Centering means engaging the interior walls of the respective eyes of the front bars serve to properly center the bolt shank therein.

This construction permits of the front bars being located very close together and yet avoids the danger of interengagement of said bars by reason of the peculiar construction of the end part of the back bar, which will be more particularly brought out as the description proceeds.

Further objects and advantages of the invention will be apparent upon reference to the following disclosure.

The invention (in a preferred form) is illustrated in the drawing and hereinafter more fully described.

On the drawing:

Figure 1 is a fragmentary plan view of an end of a bumper formed in accordance with the present invention, one part being broken away.

Figure 2 is a fragmentary vertical view, partly in section and partly in elevation, showing the manner in which the various bars constituting the bumper are joined.

Figure 3 is a fragmentary elevational view of the same.

Figure 4 is another vertical sectional view showing another detail of the invention, certain parts being shown in elevation, taken in plane IV—IV of Figure 5.

Figure 5 is a horizontal sectional view taken approximately in the plane indicated by the line V—V of Figure 2.

Referring now more particularly to the drawing, wherein the same parts are indicated throughout by the same reference characters, the upper and lower impact bars 1 and 2 respectively are provided with eyes 3 and 4 respectively. The eyes 3 and 4 are complementarily rabbeted at 5 and 6, the upper and lower walls 7 and 8 of which are adapted to engage the upper and lower edges 9 and 10 of the neck 11 between the eye 12 and the main portion 13 of the back bar.

The various eyes are assembled by holding the eyes 3 and 4 apart sufficiently to permit the back bar eye 12 to pass axially into either eye of the front bars, whereupon the other front bar eye is positioned as shown in the drawing. The shank 15 of the bolt 14 passes through the eye 12 and is provided with a circumferential flange 15 adapted to substantially fit within the upper eye 3 to thereby center the shank. The head 16 rests on the top of the eye 3. A centering element 17 having a collar 19 performs the same function with respect to the bottom of the lower eye 4 that the portions 15 and 16 accomplish with respect to the upper part of the eye 3, and is firmly held in position by the nut 18.

With the construction thus afforded, the likelihood of twisting of the various eyes is obviated, since ample bearing surface between the back bar eye 12 and the respective front bar eyes is provided. The rabbets 5 and 6 are made of sufficient width to permit of slight pivotal movement between the back bar and the impact bar, but are preferably narrower than the diameter of the back bar eye so that the latter must be inserted into the front bar eyes or nested within the same by relative axial movement. The centering portions 15 and 19 at the opposite ends of the shank of the bolt 14 provide additional reinforcement against twisting of the eyes. The bolt head is preferably integral with the shank.

It will be clear from the foregoing that the bumper end construction provided in accordance with this invention is extremely simple and yet is fully sturdy for the use to which it is to be put. The assembly provides a very neat appearance, moreover, and this construction affords advantageous use of a pair of impact bars which, while being spaced apart, nevertheless are sufficiently close together to function as well as a single bar bumper, while requiring only one back bar to cushion the same. The back bar construction may be in the form of a unitary bar clamped to both front bars, or may be made in parts having overlapped portions clamped to the

front bars or having individual separated ends connected to the front bars.

We are aware that many changes may be made and numerous details of construction may be varied through a wide range without departing from the principles of this invention, and we, therefore, do not purpose limiting the patent granted hereon otherwise than necessitated by the prior art.

10. We claim as our invention:

1. Bumper construction comprising a pair of impact bars having substantially registering eyes provided with juxtaposed slots, a back bar passing through said slots and having an eye in said eyes, one of the vertically spaced ends of said back bar eye being surrounded by one of said impact bar eyes beyond the outer limit of the respective slot, and means for holding said eyes in assembled relation.

20. 2. Bumper construction comprising a pair of impact bars having substantially registering eyes provided with juxtaposed slots, a back bar passing through said slots and having an eye in said eyes, the upper and lower ends of the back bar eye being surrounded by said impact bar eyes beyond the outer termination of said slots, and means for holding said eyes in assembled relation.

30. 3. Impact bar eye structure provided with a longitudinal slot, and a back bar extending through said slot and having an eye disposed in said structure and of a length to extend beyond the outer limits of said slot.

35. 4. Impact bar eye structure provided with a longitudinal slot, and a back bar extending through said slot and having an eye disposed in said structure and of a length to extend beyond the outer limits of said slot, said slot being spaced inwardly from the end of the bar structure, and 40 the bar structure intimately embracing the eye of said back bar beyond the outer limits of said slot.

45. 5. Bumper construction including impact bar eyes having juxtaposed slots spaced from the ends of the bars, a back bar passing through said slots and having a portion disposed in said eyes, said portion being longer than the distance between the remote walls of said slots and extending therebeyond into intimate contact with said impact bar eyes, and means for holding said eyes and 50 portion in assembled relation.

55. 6. Bumper construction comprising a pair of impact bars having spaced substantially registering eyes, a back bar having an eye registering with and bridging the space between the impact bar eyes, said impact bar eyes together providing a slot, said back bar adjacent the back bar eye being of less height than said eye and extending through said slot in engagement with the upper and lower limits of said slot, and 60 means for maintaining the parts thus engaged, the portions of the back bar eye above and below the limits of said slot being in engagement substantially throughout their respective peripheries with the respective impact bar eyes, whereby all 65 of said eyes are held in coaxial relation and twisting between said eyes is prevented.

70. 7. Bumper construction comprising a pair of impact bars having spaced substantially registering eyes, a back bar having an eye registering with and bridging the space between the impact bar eyes, said impact bar eyes together providing a slot, said back bar adjacent the back bar eye being of less height than said eye and extending through said slot in engagement with 75 the upper and lower limits of said slot, and means

for maintaining the parts thus engaged, the portions of the back bar eye above and below the limits of said slot being in engagement substantially throughout their respective peripheries with the respective impact bar eyes, whereby all 5 of said eyes are held in coaxial relation and twisting between said eyes is prevented, the reduced portion of the back bar being of greater height than the combined depths of the upper and lower portions of the slot, whereby the impact bar eyes 10 are held in spaced relation to each other.

8. An automobile bumper comprising an impact and back bar structure, said impact bar structure being provided with a terminal enclosure having an opening, said back bar structure having a portion projecting through said opening, said portion engaging the inner surface of said enclosure along a zone which substantially completely frames said opening, whereby entry of foreign matter into said enclosure through said opening 15 is prevented, and means for holding said enclosure and portion in assembly.

9. An automobile bumper comprising an impact and back bar structure, said impact bar structure being provided with a terminal enclosure 25 having an opening, said back bar structure having a portion projecting through said opening, said portion engaging the inner surface of said enclosure along a zone which substantially completely frames said opening, whereby entry of 30 foreign matter into said enclosure through said opening is prevented, and means for holding said enclosure and portion in assembly, said portion being arcuate to slide and swing within said enclosure and being of an extent to at all times 35 engage the enclosure at said zone.

10. An automobile bumper comprising an impact and back bar structure, said impact bar structure being provided with a terminal enclosure 40 having an opening, said back bar structure having a portion projecting through said opening, said portion engaging the inner surface of said enclosure along a zone which substantially completely frames said opening, whereby entry 45 of foreign matter into said enclosure through said opening is prevented, and means for holding said enclosure and portion in assembly, said portion being arcuate to slide and swing within said enclosure and being of an extent to at all times 50 engage the enclosure at said zone, said opening having walls parallel to the direction of sliding and swing movement and said back bar structure adjacent said portion being of less height than said portion and slidably engaging said walls to 55 guide said portion in its sliding and swinging movement within said enclosure.

11. An automobile bumper comprising an impact and back bar structure, said impact bar structure being provided with a terminal enclosure 60 having an opening, said back bar structure having a portion projecting through said opening, said portion engaging the inner surface of said enclosure along a zone which substantially completely frames said opening, whereby entry 65 of foreign matter into said enclosure through said opening is prevented, and means for holding said enclosure and portion in assembly, said portion being arcuate to slide and swing within said enclosure and being of an extent to at all times 70 engage the enclosure at said zone, said opening having a wall parallel to the direction of sliding and swinging movement and said back bar adjacent said portion having a notch in which said wall is received, said wall engaging the bottom of 75

the notch to guide said portion in its sliding and swinging movement within said enclosure.

12. An automobile bumper comprising an impact and back bar structure, said impact bar structure being provided with a terminal enclosure having an opening, said back bar structure having a portion projecting through said opening, said portion engaging the inner surface of said enclosure along a zone which substantially completely frames said opening, whereby entry of foreign matter into said enclosure through said opening is prevented, and means for holding said enclosure and portion in assembly, said portion being arcuate to slide and swing within said enclosure and being of an extent to at all times engage the enclosure at said zone, said opening having upper and lower walls parallel to the direction of sliding and swinging movement and said back bar structure adjacent said portion having upper and lower notches in which the respective walls are received, said walls engaging the bottoms of the notches to guide said portion in its sliding and swinging movement within said enclosure.
- 25 13. A bumper for automobiles and the like comprising a front impact structure provided with a

terminal eye having an opening of less height than the eye, and a side strip portion of less height than the front structure and projecting through said opening into and slidably and swingable pivotally within the eye, said eye including cylinder sections above and below the eye opening for engagement with the upper and lower edges of the strip portion extending through said opening, said portion being formed with cylindrical ends extending within said eye respectively above and below said edges and in engagement throughout their outer peripheries with the adjacent inner surfaces of the eye above and below said opening.

14. In a bumper end construction, a plurality of impact bars each having an eye on the end thereof, a rear bar having an eye on the end thereof, the eye on the rear bar being telescoped with eyes on the impact bars, spacing means between the ends of the eye on the rear bar and engaged by the adjacent edges of the eyes on the impact bars, and means for securing said eyes together.
